UNITED STATES PATENT OFFICE.

HENRY R. EDMONDS, OF PHILADELPHIA, PENNSYLVANIA.

SEESAW.

SPECIFICATION forming part of Letters Patent No. 366,082, dated July 5, 1887.

Application filed January 20, 1857. Serial No. 224,974. (No model.)

To all whom it may concern:

Be it known that I, HENRY R. EDMONDS, a citizen of the United States, residing at Philadelphia, in the county of Philadelphia and State of Pennsylvania, have invented a new and useful Improvement in Seesaws, or Calisthenics, of which the following is a specification.

My invention relates to improvements in seesaws; and it consists in a tilting board jointed at the center and provided with metal bearings that will open and close around a metal trunnion supported on a truss or trestle provided with sandals.

15 The objects of my improvements are, first, to construct the machine so that it may be easily taken apart and packed in a small space when not in use; second, that the seesaw may be used on carpets without injury to them. I 20 attain these objects by the mode of construction illustrated in the accompanying drawings. making a part of this specification, in which—

Figure 1 is a side elevation, and Fig. 2 a top view, of one of my improved seesaws. Fig. 3 is an edge view of the tilting board folded. All other views are separate parts in detail, and are marked by letters of reference.

Similar letters refer to similar parts throughout the several views.

30 A represents the tilting board; B, the supporting-truss; C, the trunnion upon which the board A oscillates; D, the sandals; E, the brace or tie rods; F, the metal clamp-bearings for the tilting board A, and G the hinge for jointing 35 the tilting-board A.

The construction of my improvements are as follows: The board A, I make of hard or soft wood, and in two lengths. At the center I join the two parts by means of two strap-hinges, 40 G, which hinges are fastened upon the top of the board. Under these hinges are two metal bearings, F. Each bearing is made in two parts. The hinge G and metal bearings F are fastened to the board A by rivets or bolts, as shown by 45 the dotted lines in Figs. 1 and 3.

C is a metal trunnion constructed with a collar on each end, as is plainly shown in a separate detail view.

B is a cast-metal truss made with an open slot, S, at the top, into which fits the trunnion 50 C. The sandals D are made of cast-iron or other suitable metal. These sandals are made with pockets J J and pins or lugs a a. On the bottom of the sandals are glued a piece of heavy paper or cloth. The brace-rods E are 55 made of wire, and have an eye at each end that will fit on the pins a in sandal D. To put the machine together for use, the feet of the trusses are inserted into the pockets J J on the sandals D, the brace-rods E are placed on the 60 pins a a, and the trunnion C is placed in the slot S. This makes a firm truss or trestle. The board A is then turned open so as to cause the bearing F to span the trunnion C. The board is then at liberty to oscillate on the trunnion C, 65 while it acts to hold the parts firmly together.

In taking the machine apart to pack away, the board A must be first removed, then the trunnion C, then the rods E, then the trusses from the sandals D, the board A is folded, as 70 shown in Fig. 3, and the whole machine can then be packed away in box, closet, or such place as desired, taking up but little room, and when wanted may be set up for use, as before described.

75 The sandals D, having a large base and covered with paper or cloth, will not harm or soil the floor or carpet if the machine be used in a room furnished with carpet.

The ends of the board A may be upholstered 80 with a cushion, or on each end may be placed a chair or a hobby-horse.

It is obvious that one wide hinge in place of two, as shown, may be used; also, the shape of the trusses may be changed.

85 What I claim as my invention is—

The combination, in a seesaw, of a board, A, hinge G, bearing F in two parts, trunnion C, and truss B, all substantially as set forth.

HENRY R. EDMONDS.
